UNITED STATES PATENT OFFICE

JOHN F. LARSON, OF ATTLEBORO, MASSACHUSETTS

SPINDLE CARRIER FOR BRAIDING MACHINES

Application filed June 17, 1931. Serial No. 545,128.

This invention relates to certain new and useful improvements in spindle carriers for braiding machines.

The primary object of the invention is to provide a spindle carrier for braiding machines wherein a latch device associated with the thread bobbin is released from the bobbin in the presence of tension on the thread to permit unwinding movement of the bobbin for feeding the thread.

A more specific object resides in the provision of rack and pinion devices operated by feeding movement of the thread for releasing a latch device engaged with the bobbin to permit unwinding movement of the bobbin for feeding the thread.

With the above and other objects in view that will become apparent as the nature of the invention is better understood, the same consists in the novel form, combination and arrangement of parts hereinafter more fully described, shown in the accompanying drawings and claimed.

In the drawings:—

Figure 1 is a side elevational view of a spindle carrier for braiding machines constructed in accordance with the present invention, showing guide rods for the support of a rack slide and thread slide carrying a guide pulley and pinion;

Figure 2 is a rear elevational view;

Figure 3 is a fragmentary side elevational view showing the guide pulley slide and a rack associated therewith; and

Figure 4 is a cross-sectional view taken on line 4—4 of Figure 3 showing the tensioning spring associated with the thread guide roller.

The spindle carrier comprises a base section 5 designed in the usual manner to produce a movement through a tortuous path and said base 5 has a spindle 6 rising therefrom for the support of a thread bobbin 7, the lower flange of the thread bobbin being provided with a circular series of depending ratchet teeth 8.

A block 9 carried by the upper side of the base section 5 has a pair of perpendicular guide rods 10 rising therefrom with the upper ends thereof connected by a cross head 11

that carries a guide eye 12 for threads from the bobbin 7. A cross-arm 13 extends between the guide rods 10 at a point adjacent the upper end of the bobbin 7 and carries a guide eye 14 for the bobbin thread and also a depending stop arm 15 for purposes presently to appear.

A rack frame including a rack bar 16 is slidably associated with the guide rods 10, the upper end of the rack bar 16 carrying a cross-head 17 having openings therein to receive the guide rods 10. The lower end of the rack bar 16 being attached to a plate 18 having openings therein to receive the guide rods and the lower end of said rack bar is further bent at right angles to provide a laterally extending stop arm 19 positioned beneath the lower flange of the bobbin 7 and engaged with the ratchet teeth 8.

A slide frame is mounted upon the guide rods 10 and is of substantially U-shape in top plan, having side walls 20 and a back wall 21, the lower ends of the side walls 20 flaring outwardly as at 22, while bearing flanges 23 carried by the upper edges of the side wall sections 20 are received on the guide rods 10 to provide bearings for the slide frame. A tensioned roller is journaled in the slide frame between the side wall sections 20 and in a cutaway portion 24 in the back wall 21. The guide roller 25 has a center bearing hub 26 and a laterally opening pocket 27 to receive a tensioning coil spring 28, one end 29 of which is anchored to the closed side 30 of the roller while the other end of the spring is anchored as at 31 to a rotatably adjustable disk 32 closing the side opening pocket 27, the spring 28 being rotatably tensioned by the disk 32 which is held in its adjusted position by a clamping screw 33 engaged therewith and extending through the side wall sections 20 of the slide frame as shown in Figure 4, the screw pin 33 forming a bearing for the roller 25, the disk 32 being held from rotation. A pinion 34 is fixed to a laterally extending hub portion 35 carried by the closed side of the roller 25 and is engaged with the rack bar 16. The thread 7a of the bobbin 7 passes through the guide eye 14 and then through a cross-opening 36

provided in the roller 25 to be wound once in the peripheral groove 37 in the roller, the thread 7a being then directed upwardly through the guide eye 12 at the upper end of the guide post 10.

- 5 In the normal position of the parts, the rack bar and slide frame are at their limits of lower movement, the stop arm 19 at the lower end of the rack bar being spaced from the ratchet 8 upon the lower flange of the bobbin 7. When the thread 7a is fed outwardly of the upper guide eye 12, the tensioned roller 25 carried by the slide frame is raised on the guide rods together with the slide frame 10 and said rack bar is also elevated to position the stop arm 19 in engagement with a tooth of the ratchet teeth 8, and at this time the upper end of the slide frame is engaged with the depending stop 15 upon the cross head 15 13. A further pull upon the thread 7a will rotate the roller 25 against the tension of the spring 28 and cause the pinion 34 to move the rack bar 16 downwardly for disengaging the stop arm 19 from the ratchet teeth 8 20 25 whereupon a certain quantity of thread will be unwound from the bobbin 7 and fed to the braiding machine. When tension upon the thread 7a is relieved, the roller 25 will be reversely rotated by the spring 28 and cause the rack bar 16 to be raised with the cross arm 19 again engaged with the ratchet teeth 8 to prevent further unwinding movement 30 of the bobbin 7.

From the above detailed description of the 35 invention, it is believed that the construction and operation thereof will at once be apparent and while there is herein shown and described the preferred embodiment of the invention, it is nevertheless to be understood 40 that minor changes may be made therein without departing from the spirit and scope of the invention as claimed.

I claim:—

1. In a spindle carrier for braiding machines, a base having a bobbin support rising therefrom, guide posts on the base, a rack bar 45 slideable on the posts and having a stop arm at its lower edge having ratchet engagement with a bobbin, and means operated by the bobbin thread for lowering the rack bar and stop arm to permit unwinding movement of the bobbin.
2. In a spindle carrier for braiding machines, a base having a bobbin support rising therefrom, a bobbin having ratchet teeth upon its lower flange, a stop arm engageable with the ratchet teeth and rack and pinion devices 55 operated by the feeding of the thread for disengaging the stop arm from the bobbin.
3. In a spindle carrier for braiding machines, a base having a bobbin support rising therefrom, a bobbin having ratchet teeth upon its lower flange, and rack and pinion devices 60 operated by the feeding of the thread and associated with the ratchet teeth on the bob-

bin for controlling feeding of the thread.

4. In a spindle carrier for braiding machines, a base having a bobbin support rising therefrom, a bobbin having ratchet teeth upon its lower flange, a sliding rack bar having an 70 arm positioned for engagement with the ratchet teeth, a tensioned roller over which the thread passes and a pinion carried by the roller engaged with the rack bar for disengaging the same from the bobbin. 75

5. In a spindle carrier for braiding machines, a base having a bobbin support rising therefrom, a bobbin having ratchet teeth upon its lower flange, rack and pinion devices operated by the feeding of the thread and associated with the ratchet teeth on the bobbin for controlling feeding of the thread, and means for limiting movements of the rack. 80

6. In a spindle carrier for braiding machines, a base having a bobbin support rising 85 therefrom, a bobbin having ratchet teeth upon its lower flange, a sliding rack bar having an arm positioned for engagement with the ratchet teeth, a tensioned roller over which the thread passes and a pinion carried by the 90 roller engaged with the rack bar for disengaging the same from the bobbin.

7. In a spindle carrier for braiding machines, a base having a bobbin support rising 95 therefrom, a bobbin having ratchet teeth upon its lower flange, rack and pinion devices operated by the feeding of the thread and associated with the ratchet teeth on the bobbin for controlling feeding of the thread, means for limiting movements of the rack and a 100 slide frame for the support of the pinion.

8. In a spindle carrier for braiding machines, a base having a bobbin support rising therefrom, a bobbin having ratchet teeth upon its lower flange, a sliding rack bar having an 105 arm positioned for engagement with the ratchet teeth, a tensioned roller over which the thread passes, a pinion carried by the roller engaged with the rack bar for disengaging the same from the bobbin, and a slide frame for 110 the support of the pinion.

9. In a spindle carrier for braiding machines, a base having a bobbin support rising therefrom, a bobbin having ratchet teeth upon its lower flange, rack and pinion devices operated by the feeding of the thread and associated with the ratchet teeth on the bobbin for controlling feeding of the thread, means for 115 limiting movements of the rack, a slide frame for the support of the pinion, and means for limiting movements of the slide frame.

10. In a spindle carrier for braiding machines, a base having a bobbin support rising therefrom, a bobbin having ratchet teeth upon its lower flange, a sliding rack bar having an arm positioned for engagement with the ratchet teeth, a tensioned roller over which the thread passes, a pinion carried by the 120 roller engaged with the rack bar for disengaging the same from the bobbin, a slide 125 frame for the support of the pinion, and means for limiting movements of the slide frame.

frame for the support of the pinion, and means for limiting movements of the slide frame.

11. In a spindle carrier for braiding machines, a base having a bobbin support rising therefrom, a bobbin having ratchet teeth upon its lower flange, guide posts rising from the base, a rack bar and frame slidable on the guide posts, a stop arm on the rack bar engaged with the ratchet teeth, a roller journaled on the frame over which the thread passes and a pinion carried by the roller engaged with the rack bar.

12. In a spindle carrier for braiding machines, a base having a bobbin support rising therefrom, a bobbin having ratchet teeth upon its lower flange, guide posts rising from the base, a rack bar and frame slidable on the guide posts, a stop arm on the rack bar engaged with the ratchet teeth, a roller journaled on the frame over which the thread passes and a pinion carried by the roller engaged with the rack bar, and means for rotatably tensioning the roller.

25 In testimony whereof I affix my signature.
JOHN F. LARSON.
